MOBILE CRANE

Benjamin A. Stevens, Greencastle, Pa., assignor to Grove
Manufacturing Company, Shady Grove, Pa., a corpo-
ration of Pennsylvania

Filed Sept. 12, 1968, Ser. No. 13,512

Term of patent 14 years

Int. Cl. D12—05

U.S. Cl. D14—3

Fig. 1

Fig. 2

Fig. 3

Fig. 4

Fig. 5

FIG. 1 is a side view of a mobile crane showing my design with the boom in traveling position;

FIG. 2 is a fragmentary side view of the mobile crane with the boom in elevated and extended position, the deck raised and the hood folded back;

FIG. 3 is a top view;

FIG. 4 is a front view; and

FIG. 5 is a rear view.

The dominant features of my design reside in the portions shown in full lines.

I claim:

The ornamental design for a mobile crane, substantially as shown and described.
